C. C. HANSEN

INDEPENDENT ROTATION FOR PERCUSSIVE TOOLS

Original Filed April 7, 1922

INVENTOR
Charles C. Hansen

BY
Herbert G. Ogden
HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

INDEPENDENT ROTATION FOR PERCUSSIVE TOOLS.

Original application filed April 7, 1922, Serial No. 550,421. Divided and this application filed March 5, 1923. Serial No. 622,721.

To all whom it may concern:

Be it known that I, CHARLES C. HANSEN, a citizen of the United States, and a resident of Easton, county of Northampton, and 5 State of Pennsylvania, have invented a certain Independent Rotation for Percussive Tools, of which the following is a specification, accompanied by drawings.

This invention, which is a division of my 10 copending application, Serial No. 550,421, filed April 7, 1922, relates to fluid actuated percussive tools, such as rock drills, which may be of the hammer type but relates more particularly to means independent of the 15 piston for imparting rotation to the drill steel.

The objects of the present invention are to simplify and reduce the cost of construction of the rotation motor, enable the motor 20 to be conveniently mounted at the side of the back end of the cylinder, and produce a construction by means of which the motor and its operative driving connections may be readily assembled and disassembled in 25 the machine.

Further objects of the invention will hereinafter appear and the invention is shown in one of its preferred forms in the accompanying drawings, in which—

30 Figure 1 is a side elevation partly broken away and partly in longitudinal section of so much of a rock drill as will serve to illustrate the invention;

35 Figure 2 is a horizontal sectional plan view on the line 2—2 of Figure 1, and

Figure 3 is a detail transverse sectional view of the motor on the line 3—3 of Figure 2 looking in the direction of the arrows.

Referring to the drawings, the cylinder A, 40 is provided with a fluid actuated reciprocating hammer piston B of any suitable type, and the drill steel C extends into the front head D in position to receive the impact blows of the piston. Motive fluid for operating the piston is supplied to the machine at the inlet E controlled by the throttle valve F in the back head G and the cylinder A, front head D and back head G are held together by the usual side bolts H.

50 Rotation is imparted to the drill steel C by means of a rotation motor, in this instance shown as a rotary gear motor, having the gears J and K suitably mounted in a motor casing I, which is adapted to be

removably mounted at the side of the rearward end of the cylinder A and one of the gears, as the gear K is operatively connected to rotate the drill steel through driving connections constructed in accordance with my invention.

As shown, the cylinder is formed with a reduced extension O and a projection forming a shoulder P at the rearward end of the cylinder, located forwardly of the back end Q of the cylinder extension and formed with 60 a plane face.

The motor casing L, as shown, is open at the front end and preferably provided with an integral back head R, although the back head could be a separate plate if desired. 70 The open end of the motor casing L is adapted to be secured against the plane face or surface of the projection P on the cylinder, which thereby forms one head of the motor casing. The motor casing is thus located 75 adjacent or in proximity to the cylinder extension O, and preferably does not bear upon the cylinder extension, but a space S is left between the bottom of the motor casing and the cylinder extension, which permits the motor to exhaust through the exhaust openings T into the space S beneath the motor, and from thence to atmosphere. 80 The space or passage S', between the back head G and the motor casing, Fluid 85 pressure is supplied to the motor casing through the admission port U from a port V in the back head G communicating with the supply controlled by the throttle valve F.

The construction described avoids the necessity of machining the surface of the cylinder extension O beneath the motor, and requires only that the plane surface or face of the cylinder projection P be machined to 95 form a tight fit with the motor casing. The motor casing is readily secured and centered upon the cylinder projection P as by means of longitudinal bolts W passing through the motor casing and the cylinder 100 projection, and by this means the bolts are better able to resist longitudinal strains.

The cylinder back head G is suitably centered over the back end of the cylinder extension O in any suitable manner, in this instance the back head G being provided with the flange X, only a portion of which is shown for illustrative purposes. The back

head G forms a back head for the cylinder and also extends outwardly over the motor casing, and a suitable packing Y may be provided between the back head G and the 5 motor casing, to connect the port V in the back head with the port or passage U in the motor casing.

The gears J and K are preferably interchangeable and each provided with keyways *a*, so that either gear or any gear of 10 this construction may be keyed to the section *b* of the driving shaft, as by means of a key *c*. The gear J rotates on roller bearings *d* on the stationary shaft *e* having bearings 15 in the motor casing, and cylinder projection respectively. The driving shaft is preferably formed in rearward and forward sections *b* and *f* suitably coupled together as by means of the undercut and overlapping 20 portions *g* and *h*, and a loose sleeve *j* is placed over the shaft and extends over the coupling members within the chamber *h*, in the cylinder A through which the shafts extends. The rearward shaft section *b* rotates 25 in a roller bearing *o* in the back head R of the motor casing, and in a roller bearing *p* carried in the bushing *q* in the body portion of the cylinder. The forward shaft section *f* rotates in the roller bearing *r* carried in 30 the bushing *s* at the forward end of the cylinder body. Slight clearance is provided between the ends of the shaft sleeve *j* and the roller bearing bushings *q* and *s* so that when the motor casing and motor gears are 35 removed from the machine, thus separating the shaft section *b* from the shaft section *f*, but leaving the roller bearing *p* in position, the shaft sleeve *j* may be utilized to push the roller bearing *p* from the bushing *q*. Obviously, after the front head D of the machine 40 has been removed, and the parts connected therewith, including the roller bearing *r*, a tool may be inserted against the shaft sleeve *j* to push the sleeve longitudinally.

45 Suitable gear connections are provided for transmitting rotation from the driving shaft of the motor to the drill steel, and for this purpose the shaft section *f* is provided with a pinion *t* meshing with a gear *u* having a 50 pinion *v* meshing with a gear *w*, which is suitably secured as by means of screw threads *x* to the chuck *y* for rotating the chuck. A chuck sleeve *z* is preferably inserted within the back end of the chuck, and 55 the chuck bushing 2 is inserted in the chuck against the chuck sleeve *z*. The chuck *y* is suitably clutched to the chuck key 3 and rotation is imparted to the drill steel through the agency of the usual lugs 4 on the shank of 60 the steel, which engage the chuck *y*. Within the front end of the cylinder is preferably located the front cylinder bushing 5 through which the forward extension 6 of the piston B reciprocates, and in order to provide air 65 for blowing down through the drill steel the

piston extension 6 is preferably formed with several grooved or flattened portions 7, so that air may blow through said grooves or flattened portions from the cylinder when said grooves enter the cylinder as the piston 70 moves to the end of its rearward stroke.

I claim:

1. In a fluid actuated percussive tool, the combination of a cylinder and reciprocating piston, and a fluid pressure rotation motor mounted at the side of the rearward end of the cylinder and operatively connected to rotate the drill steel, said motor having a casing, a back head for said motor casing, rotary gears mounted in said motor casing, a sectional driving shaft having forward and rearward sections slidably coupled together, the rearward section being keyed to one of the gears, and having anti-friction bearings in the said back head and 80 in the body portion of the cylinder, the forward shaft section having an anti-friction bearing at the forward end of the cylinder body, and a loose shaft sleeve over said shaft coupling, whereby the motor may be 85 dismounted without removing the entire driving connections.

2. In a fluid actuated percussive tool, the combination of a cylinder and reciprocating piston and a fluid pressure rotation motor 95 mounted at the side of the rearward end of the cylinder and operatively connected to rotate the drill steel, said motor having a casing open at the front end and adapted to be removably secured against a plane 100 face of the cylinder, a back head for said motor casing, rotary gears mounted in said motor casing, a sectional driving shaft having forward and rearward sections slidably coupled together, the rearward section being keyed to one of the gears and having anti-friction bearings in the said back head and 105 in the body portion of the cylinder, the forward shaft section having an anti-friction bearing at the forward end of the cylinder body, and a loose shaft sleeve over 110 said shaft coupling, whereby the motor may be dismounted without removing the entire driving connections.

3. In a fluid actuated percussive tool, the combination of a cylinder and reciprocating piston and a fluid pressure rotation motor mounted at the side of the rearward end of the cylinder and operatively connected to rotate the drill steel, said motor having a casing, a back head for said motor casing, rotary gears mounted in said motor casing, a sectional driving shaft having forward and rearward sections slidably coupled together, the rearward section being keyed to one of the gears, an anti-friction bearing 115 for said rearward shaft section in the said back head, a bearing bushing and anti-friction bearing therein for the rearward shaft section in the body portion of the cylinder, a bearing bushing and anti-friction bearing 120 125 130

ing therein for the forward shaft section at the forward end of the cylinder body, and a loose shaft sleeve over said shaft coupling, whereby the motor may be dismounted without removing the entire driving connections.

4. In a fluid actuated percussive tool, the combination of a cylinder and reciprocating piston and a fluid pressure rotation motor 10 mounted at the side of the rearward end of the cylinder and operatively connected to rotate the drill steel, said motor having a casing, a back head for said motor casing, rotary gears mounted in said motor casing, 15 a sectional driving shaft having forward and rearward sections slidably coupled together, the rearward section being keyed to

one of the gears, an anti-friction bearing for said rearward shaft section in the said back head, a bearing bushing and anti-friction bearing therein for the rear shaft section in the body portion of the cylinder, a bearing bushing and anti-friction bearing 20 therein for the forward shaft section at the forward end of the cylinder body, and a 25 loose shaft sleeve over said shaft coupling having appreciable clearance between the ends of the sleeve and the said bearing bushings, whereby the sleeve may be moved relatively to the bushings for disassembling 30 the bearings.

In testimony whereof I have signed this specification.

CHARLES C. HANSEN.
